UNITED STATES PATENT OFFICE.

FRANK CARTLIDGE, OF TERRE HAUTE, INDIANA, ASSIGNOR TO SULLIVAN MACHINERY COMPANY, A CORPORATION OF MASSACHUSETTS.

MINING MACHINE.

Application filed June 12, 1915, Serial No. 33,650. Renewed July 26, 1921. Serial No. 487,724.

To all whom it may concern:

Be it known that I, FRANK CARTLIDGE, a citizen of the United States, residing at Terre Haute, in the county of Vigo and State of Indiana, have invented a new and useful Mining Machine, of which the following is a specification.

This invention relates to mining machines, and more particularly to mining machines of the type comprising kerf cutting mechanism and adapted to be propelled and guided relative to a mine bottom by flexible feeding and guiding mechanism including flexible feeding and guiding portions and means cooperating therewith to determine the movements of the machine.

An object of the invention is to provide an improved mining machine. Another object is to provide an improved mining machine having improved feeding means. A further object of the invention is to provide an improved mining machine having improved feeding means by which feeding may be accomplished at predetermined cutting and higher speeds. A still further object of the invention is to provide an improved mining machine in which a single driving motor cooperates with improved cutting mechanism actuating and feeding mechanism to effect cutting and an improved control of the machine during cutting and also during moving over a mine bottom at other times and in which the parts are exceedingly compactly arranged. Another object of the invention is to provide an improved feeding mechanism wherein an improved control is secured and in which more particularly the feeding is automatically controlled by the load due to the resistance to cutting whereby the speed of the feeding is dependent upon and preferably varies in inverse sense to the load on the cutter. It is a still further object of the invention to secure this automatic control electrically and by mechanism which requires but a small amount of force for its feed controlling operation thereof though controlling a heavy machine, which is arranged in such a compact manner that it can be used in the very narrow space which is usually available for mining operations, which is self-oiling, and in which the driving motor, when an electric motor, can be

either a direct or an alternating current motor, without any possibility that the alternating current motor will be stalled. Further objects and advantages of the invention will hereinafter appear.

In the accompanying drawings I have shown for purposes of illustration two forms which my invention may assume in practice.

In these drawings,

Fig. 1 is a plan view of the machine employing the preferred form of my invention, with the cutter partly broken away; Fig. 2 is a side elevation of such mining machine, with some of the parts in section to show the driving mechanism; Fig. 3 is a partial section on the line 3-3 of Fig. 1; Fig. 4 is a view showing the gear connections for the feeding mechanism; Fig. 5 is a section on the line 5-5 of Fig. 1; Fig. 6 is a fragmentary view showing a modified form of my invention; Fig. 7 is a section on the line 7-7 of Fig. 6; Fig. 8 is a diagrammatic view showing the electrical connections when the driving motor is an electric motor of the commutator type; and Fig. 9 is a similar diagrammatic view, showing the connections when the driving motor is an alternating current motor of the squirrel cage type.

The main frame 10 of the machine has a substantially flat bottom and carries all the working parts. The power for driving and feeding is furnished by a single electric motor 11, which rests on a horizontal shelf 12 of the main frame 10, such shelf being spaced some distance above the bottom of the frame to provide a space for the cutter chain as hereinafter apparent. On the shaft of the motor 11 is a bevel pinion 13, which meshes with a bevel gear 14 having an elongated hub 15 which is keyed to a vertical shaft 16 which is hung from its upper end on an adjustable thrust bearing 17 supported in a removable cap plate 18 and located in a pocket formed by an up-standing flange 19 surrounded by a cap 20, which may be removed to fill such pocket with oil or other lubricant. The cap plate 18 also has a downwardly extending flange 21, which surrounds the hub 15 and between which and such hub 15 is a bushing 22, which is kept filled with oil by an up-standing flange 23 carried by the gear 14 and surrounding but

spaced from the flange 21. The oil from the pocket formed by the flange 19 passes down along the bearing surfaces of the bushing 22, and in order to escape must overflow the flange 23. The shaft 16 is further supported by a bushing 24 in the floor of the gear casing 25, which bushing rises a considerable distance above such floor so as to maintain such gear casing partly full of oil, and by a bushing 26 mounted in an up-standing flange 27 from the bottom of the main frame 10, the bushing 26 being closed at the bottom to enclose the lower end of the shaft 16. The bearing surfaces of the bushing 26 are lubricated by the oil which overflows from the gear casing 25 through the bushing 24, and also by an overflow pipe 28 which opens into such gear casing at about the level of the top of the bushing 24 and leads downward through the floor of such gear casing to communicate with the bushing 26. For further lubrication of the driving pinion 13, an oiling idler 29 may be mounted on the main frame 10 to mesh with such pinion and to dip into the oil in the gear casing 25.

Below the floor of the gear casing 25 but above the upper end of the bushing 26 a pinion 30 is fixed on the shaft 16. This pinion 30 meshes with a gear 31 mounted on a shaft 32, which has bearings in bushings mounted in an up-standing circular flange 33 from the bottom of the main frame 10 and in an up-standing flange 34 from the floor of the gear casing 25, the flange 34 being located between some of the parts hereinafter described and overlapping therewith for economy in space. As shown the lower end of the shaft 32 is also lubricated from the casing 25, a suitable passage 32' in the bottom of the main frame supplying lubricant thereto from the bushing 26 which, as shown, has a suitable port 26' communicating with said passage. The gear 31 carries a driving sprocket 35, for a cutter chain 36, which is mounted on such sprocket 35 and travels around a suitable projecting frame 37 which extends into the vein of coal to be cut, the frame 37 being supported and the chain 36 being located in the space between the shelf 12 and the bottom of the main frame 10. The cutter chain 36 has the usual cutters 38. Thus the motor 11 drives the cutter chain 36 through the pinion 13, gear 14, shaft 16, pinion 30, gear 31, and sprocket 35.

A worm 40 is fixed on the shaft 16 between the floor of the gear casing 25 and the gear 14. The lower end of this worm projects loosely over the upper end of the bushing 24. The worm 40 meshes with a worm gear 41 mounted on a horizontal stub or jack shaft 42. From this shaft 42 the feeding mechanism is driven.

In that form of my invention which I shall specifically prosecute herein and which

is shown in Figs. 1 to 5 inclusive, the shaft 42 has fixed thereon two duplicate pinions 43 which mesh respectively with two duplicate gears 44 mounted on sleeves 45 and 46 respectively, which sleeves are co-axial with 70 and rotatable relatively to a horizontal shaft 47, the sleeve 45 fitting directly on a bushing on the shaft 47. The two gears 44 are spaced apart, but are connected to rotate together by bolts 48, on each of which bolts 75 are mounted two planet gears 49 and 50 of slightly different size but rigid with each other so as to rotate together. The gears 49 are shown as slightly larger than the gears 50. The planet gears 49 mesh with a sun gear 51, and the planet gears 50 with a sun gear 52, the sun gear 51 being larger than the sun gear 52 to correspond with the difference in size of the planet gears 49 and 50. The reason for having the pinions 43 85 and gears 44 duplicated is merely to eliminate all tendency to twist in the planet gears 49 and 50 and the sun gears 51 and 52. The sun gear 52 is fast on the shaft 47. The sun gear 51 forms part of a sleeve 53 rotatably mounted on said shaft and located between such shaft and the sleeve 46. A sliding sleeve 54 has sliding toothed connection with the sleeve 53, and is slidable in either direction along such sleeve by a finger 55 which may be operated by a shift lever 56. The sleeve 54 is provided with teeth on both axial ends, so that when slid in one direction from neutral position, in which it is free from any locking engagement, the teeth 57 on one end engage teeth 58 on the end of the sleeve 46, to lock together the sleeves 46 and 53 and thus cause the sun and planet mechanism to revolve as a unit; and when slid in the other direction from neutral position, the teeth 59 on the other end engage teeth 60 on a worm wheel 61, loose on the shaft 47, to lock together said worm wheel 61 and the sleeve 53. The worm wheel 61 meshes with a worm 110 62, the pitch of which is such that it can be driven, though with small force, by the worm wheel 61. The worm 62 is mounted in thrust bearings 63, and is provided at one end with a bevel gear 64 which meshes with a bevel pinion 65 on a vertical shaft 66. A clutch or brake casing 67 is loosely mounted on the shaft 66 near its upper end, and is provided with a surrounding brake band 68 which may be set to any desired tightness by a thumb screw 69 passing through its ears 70. The ears 70 are located in a lateral pocket 71 of the gear casing 25, the walls of which pocket restrain the ears 70 and prevent the brake band 68 from turning. Thus by setting or releasing the thumb screw 69, which can be done with very small force, the brake casing 67 may be held stationary or released at will. Between the brake casing 67 and a collar 72 carried by the shaft 66 is located 130

a multiple disk clutch or brake 73, which is likewise curved below the gears 44, 49, and 50, and 61 and 62 to project downward into the hollow upper face of the gear 31, and to provide an oil-tight casing for the gears first-named, so that in operation they may be thoroughly lubricated. 5

10 The annulus 74 is provided with a peripheral flange 77, which may be engaged by a pair of rollers 78 mounted on a forked lever 79. This lever 79 straddles the annulus 74, is pivotally mounted at its forked 15 end on a pair of fixed pivot pins 80, suitably supported from the frame, and at the other is pivotally connected to the upper end of a vertically movable core 81 of a solenoid 82. The rollers 78 are quite close to the pivot 20 pins 80, and are normally held clear of the flange 77 by a compression spring 83 which bears upward against the under end of an adjusting screw 84 carried by the lever 79 near the core 81.

25 The solenoid 82 is connected in series with the motor 11 across any suitable supply circuit 85, through any suitable switch 86 and controlling device 87. The motor 11 is shown in Fig. 8 as a compound wound motor 30 of the commutator type, and in Fig. 9 as an induction motor of the squirrel cage type. Because of the series connection of the solenoid 82, the pull of such solenoid varies directly as the load on the motor 11, which 35 load is in the main that due to the cutting mechanism. If desired, a switch 88 may be provided for short-circuiting the solenoid 82.

The feed control mechanism just described is for controlling the speed of the shaft 47, 40 which overhangs at one end and is there provided with a gear 90, which meshes with an internal gear 91 on a feed operating member herein in the form of a winding drum 92, for driving the latter. This winding drum 45 may have wound on it a rope or cable, which extends from it and over any desired ones of the pulleys 93, to move the whole mining machine in the desired direction as the rope or cable is wound up on the drum 92, a second rope or cable being provided on and controlled by a friction controlled take-up drum 94 so that after the cutter bar has been sumped into a mine face, the machine 50 may be moved bodily laterally along the face to under cut the same in a well known manner.

For the sake of compactness, the flange 34 which receives the upper end of the shaft 32 projects up between the gears 44 on the one hand and the worm wheel 61 and worm 55 62 on the other hand, and these gears all project down into the hollow upper face of the gear 31, which is shaped to receive them, so that the total height of the machine may be as small as possible. The gear casing 25

is set and released by axial movements of the brake casing 67. The brake casing 67 rests on an annulus 74 surrounding the shaft 66 and spring-pressed upward by a compression spring 75 located between such annulus and a thrust bearing 76, so that the annulus 74 and spring 75 may rotate with the shaft 66 if necessary. The spring 75 sets the clutch 73. The annulus 74 is provided with a peripheral flange 77, which may be engaged by a pair of rollers 78 mounted on a forked lever 79. This lever 79 straddles the annulus 74, is pivotally mounted at its forked end on a pair of fixed pivot pins 80, suitably supported from the frame, and at the other is pivotally connected to the upper end of a vertically movable core 81 of a solenoid 82. The rollers 78 are quite close to the pivot pins 80, and are normally held clear of the flange 77 by a compression spring 83 which bears upward against the under end of an adjusting screw 84 carried by the lever 79 near the core 81.

25 The solenoid 82 is connected in series with the motor 11 across any suitable supply circuit 85, through any suitable switch 86 and controlling device 87. The motor 11 is shown in Fig. 8 as a compound wound motor 30 of the commutator type, and in Fig. 9 as an induction motor of the squirrel cage type. Because of the series connection of the solenoid 82, the pull of such solenoid varies directly as the load on the motor 11, which 35 load is in the main that due to the cutting mechanism. If desired, a switch 88 may be provided for short-circuiting the solenoid 82.

The feed control mechanism just described is for controlling the speed of the shaft 47, 40 which overhangs at one end and is there provided with a gear 90, which meshes with an internal gear 91 on a feed operating member herein in the form of a winding drum 92, for driving the latter. This winding drum 45 may have wound on it a rope or cable, which extends from it and over any desired ones of the pulleys 93, to move the whole mining machine in the desired direction as the rope or cable is wound up on the drum 92, a second rope or cable being provided on and controlled by a friction controlled take-up drum 94 so that after the cutter bar has been sumped into a mine face, the machine 50 may be moved bodily laterally along the face to under cut the same in a well known manner.

For the sake of compactness, the flange 34 which receives the upper end of the shaft 32 projects up between the gears 44 on the one hand and the worm wheel 61 and worm 55 62 on the other hand, and these gears all project down into the hollow upper face of the gear 31, which is shaped to receive them, so that the total height of the machine may be as small as possible. The gear casing 25

In operation, the motor 11 drives the cutter chain 36 continuously through the driving connection already set forth; as long as the motor is supplied with current. The 75 motor 11 also drives the gears 44 continuously, through the bevel pinion 13, bevel gear 14, worm 40, worm wheel 41, shaft 42, and pinions 43, and the rotation of the gears 44 causes the planet gears 49 and 50 to 80 travel around the axis of the shaft 47. If the parts are in the position shown in Fig. 5, this travel of the planet gears 49 and 50 is without effect on the shaft 47 and produces no feeding operation, because the gear 51, which may be called the reaction gear, is free to rotate, and so there can be no reaction against it to cause a movement of the shaft 47, which is subject to the resistance offered to the feeding of the machine. If 90 a quick feeding is desired, as for moving the machine from place to place or setting it, the shift lever 56 is thrown to cause intermeshing of the teeth 57 and 58, thus locking the sleeves 46 and 53 together and causing 95 the sun and the planet mechanism to revolve as a unit and the shaft 47 to rotate at the same speed as the gears 44. If a slow feeding is desired, the shift lever 56 is thrown to cause intermeshing of the teeth 59 and 60, 100 whereupon the travel of the planet gears 49 and 50 tends to produce movements of the sun gears 51 and 52 in opposite directions, the sun gear 52 tends to drive the winding drum 92, through the shaft 47 and gears 90 105 and 91, and the sun gear 51, which is the reaction gear, tends to drive the shaft 66, through the intermeshing teeth 59 and 60, the worm wheel 61, the worm 62, and the bevel gears 64 and 65. This tendency to 110 drive the gears 51 and 52 in opposite directions may be controlled by hand by the thumb screw 69. If such thumb screw is loosened, the brake casing 67 may rotate freely, thus allowing the reaction gear 51 115 to rotate and preventing it from furnishing the reaction necessary to cause movement of the sun gear 52 and winding drum 92. By tightening the thumb screw 69, any desired amount of resistance may be offered 120 to the rotation of the brake casing 67, or such brake casing may be locked against movement, thus retarding or stopping the movement of the reaction gear 51 and providing the necessary resistance for the sun gear 52 to react against in order for it to 125 rotate to turn the winding-drum 92. Thus by adjusting the thumb screw 69 the feeding of the machine may be controlled by hand. This hand control, however, can not pro-

duce more than a given load on the motor 11; for as the thumb screw 69 is tightened and the brake casing 67 is retarded or stopped in its rotation, the forward feeding of the machine may impose a load on the cutting chain 36, and therefore on the motor 11, and this load causes a larger current to be drawn by the motor 11. This larger current causes the solenoid 82 to exert a greater pull on its core 81, and when the current is sufficiently great the solenoid draws down the core 81 against the action of the spring 83. The spring 83 may be adjusted by the screw 84 to cause the solenoid to act to any desired current. As the core 81 is drawn down, the rollers 78 approach and finally engage the flange 77, and if the current drawn by the motor 11 still increases the continued downward movement of the core 81 because of such increased current causes the rollers 78 by their action on the flange 77 to depress the annulus 74 and to release the clutch or brake 73 to a greater or less extent, thus permitting the shaft 66 to rotate more or less freely even though the brake casing 67 is retarded or held stationary. This releasing of the clutch 73 and the resultant rotation of the shaft 66 permits the reaction gear 51 to rotate and thus removes the resistance against which the sun gear 52 must react in order to produce rotation of the winding drum 92, and thus either diminishes or completely stops the forward feeding of the machine, according to the increase in the load. As soon as the action of the cutting mechanism has caused the load to diminish, the current drawn by the motor falls, the solenoid 82 allows the core 81 to rise, and the spring 75 causes a more or less complete resetting of the clutch 73, thus again stopping or retarding the reaction gear 51 and furnishing the necessary resistance for the forward driving of the sun gear 52 and the winding drum 92. The solenoid may be made to operate its core through the entire range of movement on a comparatively small variation in current, thus maintaining the load and the current demanded thereby substantially constant within narrow limits. The load cannot be made to exceed this upper limit by any manipulation of the thumb screw 69.

In practice, the machine after once having been set in position, is allowed to operate automatically, the thumb screw 69 being tightened to hold the brake casing 67 absolutely stationary, and the solenoid 82 controlling the setting and releasing of the brake 73 as required in order to maintain the load on the motor 11 substantially constant, and to vary the rate of feeding in inverse proportion to such load. Yet the rate of feeding can also be controlled manually, at will, and this can be done without any danger that the manual control will produce

too great a load on the motor, as the automatic controlling devices are always in readiness to assume the control when the load reaches a predetermined value. The rate of feeding can be varied as desired so long as the load on the motor produced by reason of such feeding remains below a predetermined value, but cannot be varied by the manual control means, which is the thumb screw 69, to produce a greater load than this predetermined maximum. In addition, the load control makes it absolutely impossible to stall the motor, by preventing an overload; thus making it possible to use alternating current motors without the usual danger of their stalling, and of the consequent short circuit on the supply line.

It will be seen that, should the cutting mechanism strike an obstruction, thereby arresting the movement of the machine, the increased load imposed upon the motor will cause the operation of the feeding mechanism to be immediately stopped by operatively disconnecting the same from the motor, said feeding mechanism being thereafter reconnected when the obstruction is removed, all without stopping the action of the cutting mechanism and independently of the relative movement thereof.

In the form of my invention described above and shown in Figs. 1 to 5 inclusive, the automatic and manual clutch-controlling means both control the connection of the reaction gear to a stationary part, so as to allow more or less slipping between the reaction gear and the stationary part. It is not necessary, in the broader aspect of my invention, that this clutch be thus located. In the arrangement shown in Figs. 6 and 7, a modified form of the invention is shown, in which this clutch controls the connection between the reaction gear and other parts of the variable speed drive for the feeding mechanism.

In this modified form of my invention, the shaft 16 carries the worm 40 which meshes with the worm wheel 41 fixed on the shaft 42 exactly as in the form shown in Figs. 1 to 5 inclusive, so that such shaft is driven constantly by the motor 11 when such motor is in operation. However, instead of having two pinions 43 fast on the shaft, as in the arrangement first described, two pinions 43' are mounted on a sleeve 100 which is loosely mounted on the shaft 42 and is fixed to a clutch casing 67', between which and the shaft 42 is a multiple disk clutch 73'. When the clutch 73' is set, the sleeve 100 and gears 43' rotate with the shaft 42, but when the clutch 73' is released, there is more or less slippage between the shaft 42 and the sleeve 100, the amount of such slippage depending upon the degree to which the clutch is released. The setting and releasing of the clutch 73' is controlled by a

- plurality of levers 101 pivoted on the clutch casing 67' and bearing against the end disk of the multiple disk clutch 73', said levers being operated by a sliding sleeve 74' mounted on the shaft and spring-pressed to a position to set the clutch 73 by a spring 75' which surrounds the hub of the disk 74' and acts between such disk and a thrust bearing 76' bearing against the gear casing 25. The disk 74' has a peripheral flange 77', which may be engaged by a pair of rollers 78' mounted on a forked lever 79' which straddles the disk 74' and is pivotally mounted on a fixed pivot pin 80' suitably supported on the frame or casing 25. The lever 79' is connected to the movable core 81 of the solenoid 82, which are the same and act in the same way, as in the form shown in Figs. 1 to 5 inclusive.
- 20 The pinions 43' mesh with duplicate gears 44 of a planetary gear structure exactly like that in the arrangement shown in Figs. 1 to 5 inclusive, including the same gears 44, sleeves 45 and 46, shaft 47, bolts 48, planet gears 49 and 50, sun gears 51 and 52, sleeve 53, sliding sleeve 54 splined on the shaft 53, finger 55, shift lever 56, teeth 57, 58, and 59. Instead of teeth 60 on a worm wheel, however, there are teeth 60' on a fixed member 102, so that when the teeth 59 and 60' are in engagement the reaction gear 51 is positively held stationary.
- 25 In the operation of the arrangement shown in Figs. 6 and 7, the same general results are obtained as in that shown in Figs. 1 to 5 inclusive. When the sleeve 54 is in its middle position no feeding is obtained, as the reaction gear 51 is free to rotate. When the sleeve 54 is thrown to the right to cause intermeshing of the teeth 57 and 58 a quick feeding is prevented from causing an overload on the motor by the action of the solenoid 82 on the clutch 73'. When the sleeve 54 is thrown to the left to 30 cause intermeshing of the teeth 59 and 60', the reaction gear 51 is positively held stationary, so that when the clutch 73' is set the shaft 47 is driven to operate the drum 92, exactly as in the arrangement shown in Figs. 1 to 5 inclusive. However, if the feeding which results from this operation of the drum 92 causes the load on the motor to demand too great a current, the solenoid 82 draws in its core 81 and thereby operates 35 the lever 79' to move the disk 74' to the right against the spring 75' to release the clutch 73' to a greater or less extent, thus allowing slipping between the reaction gear 51 and the shaft 42 and thereby diminishing 40 or stopping the feeding action of the drum 92. As the load on the motor varies, the core 81 is moved in or out to cause a releasing or setting of the clutch 73' and thus to 45 control slippage of the shaft 42 in the sleeve 50 100 in accordance with the load, so that the feeding operation always maintains the load on the motor at a substantially constant value.
- 50 Manual means may be provided for releasing the clutch 73'. As shown, one or more rollers 103 are carried by a slideable member 104 which is screw-threaded and provided with a nut 105 which co-operates with the casing 25 to slide the member 104. The rollers co-operate with the flange 77' of 55 the disk 74' to shift such disk against the spring 75' to release the clutch 73'. Manipulation of the manually controlled nut 105, however, can not cause an undue increase of load on the driving motor 11, because the rollers 78' are always in readiness for operation by the solenoid 82 to release the clutch 73' whenever the load on the motor requires it.
- 55 The species of my invention last described 85 forms the subject matter of my divisional application, Serial No. 722,373, filed June 25, 1924.
- 60 As a result of my improved construction 90 it will be noted that it is possible to control the feed of the mining machine and the controlling means therefor by means responsive to the resistance to cutting in such a manner as to make the operation of the machine automatic in this respect and eliminate the abuses of the machine possible in the hands of an ignorant operator. Attention is also directed to the fact that through my improved construction it is made possible not 95 only to control the feed over a wide range through my improved reaction gearing, but also to simplify and improve the connections between the motor armature and the feed operating member, my improved reduction mechanism being carried on only 100 two transverse members, herein shafts, one of which is connected to the motor armature and the other of which is connected to the feed operating member, and so arranged 105 with its meshing elements on each of said members that not only may one member assume the form of a stub or jack member, but that the two members may be disposed adjacent one another and directly connected. 110 Through the provision of my improved variable speed transmission mechanism connected between the transverse members, it will be observed that it is also made possible 115 while maintaining this simplified arrangement to drive the feed operating member at a plurality of predetermined speeds and if desired have each subject to friction control as shown in the modified construction illustrated. Further it will be noted that 120 through my improved connection to the worm including the bevel gear rotatable on an upstanding axis above the worm, it is made possible to simplify the driving connection between the latter and the armature 125 shaft and at the same time to permit the 130

- bevel gear to be removed through the top of the frame whenever it is desired to obtain access to the worm and the other cooperating gearing. Moreover, as a result of my 5 improved construction including the cutter chain sprocket on a stub shaft and the connection of the feed operating member and cutter chain driving mechanism to means on the upstanding member driven by the 10 overlying bevel gear, it will be observed that it is made possible to produce an exceedingly compact construction while at the same time giving a relatively large space above the sprocket for the feed driving 15 mechanism. By driving the cutter chain sprocket through the large hollowed-out spur gear meshing with the spur pinion on the upstanding member, these advantages are further accentuated, while by the use of 20 the large cutter chain sprocket driving gear located as disclosed and rotatable at the speed obtained this gear is also rendered adaptable to use as a truck driving gear meshing directly with a cooperating meshing member on truck driving mechanism of 25 standard construction. By the provision of my improved lubricant containing casing, it is also made possible to maintain the feed gearing properly lubricated while through 30 the provision of my improved connections between the casing and the cutter chain driving sprocket, it is made possible to keep this element automatically lubricated from the casing. These and other advantages of 35 my improved construction will, however, be clearly apparent to those skilled in the art.
- This application is a continuation in part of the application which has matured into my Patent 1,173,170, granted Feb. 29, 1916. 40
- While I have in this application specifically described several forms which my invention may assume in practice, it will be understood that these forms of the same are shown for purposes of illustration and that 45 the invention may be modified and embodied in other forms without departing from its spirit or the scope of the appended claims.
- I claim as my invention:
- 50 1. In combination, a cutter, a driving motor therefor, a feeding device for feeding said cutter, said feeding device being driven from said driving motor, and means for automatically varying the speed of operation of said feeding device in relation to that of said driving motor to maintain the load on the cutter constant, and for manually varying the speed of operation of said feeding mechanism with relation to that of the driving motor to reduce the load on the cutter to any value below that at which the feeding is controlled automatically.
- 55 2. In combination, a cutter, a driving motor therefor, a feeding device for feeding said cutter, said feeding device being driven
- from said driving motor, and means for automatically varying the speed of operation of said feeding device in relation to that of said driving motor to maintain the load on the cutter constant. 70
3. In combination, a driving motor, a working device driven by such motor, a feeding device, a gearing through which said feeding device is driven, said gearing including two members between which said driving motor produces a reaction, a stationary part, one of said members being connected to said feeding device, an automatic clutch and a manually-controlled clutch one of which acts through the other to connect parts of said gearing through the other of said members to the stationary part and both of which must be set to produce the reaction, and means responsive to the load on said working device for controlling 75 said automatic clutch. 80
4. In combination, a driving motor, a working device driven by such motor, a feeding device, a gearing through which said feeding device is driven, said gearing including two members between which said driving motor produces a reaction, one of said members being connected to said feeding device, a stationary part, an automatic clutch acting to connect parts of said gearing through said second member to the stationary part, and means responsive to the load on said working device for controlling 85 said automatic clutch. 90
5. In combination, a driving motor, a working device driven by such motor, a feeding device, a gearing through which said feeding device is driven, said gearing including two members between which said driving motor produces a reaction, one of said members being connected to said feeding device, a stationary part, an automatic clutch and a manually-controlled clutch one of which acts through the other to connect parts of said gearing through the other of 95 said two members to the stationary part and both of which must be set to produce the reaction, and an electro-magnetic device which is energized in proportion to the load on said working device and acts to release 100 said automatic clutch progressively as such load increases. 105
6. In combination, a driving motor, a working device driven by such motor, a feeding device, a gearing through which said feeding device is driven, said gearing including two members between which said driving motor produces a reaction, one of said members being connected to said feeding device, a stationary part, an automatic clutch acting to connect parts of said gearing through said second member to the stationary part, and an electro-magnetic device which is energized in proportion to the load on said working device and acts to re- 110 115 120 125 130

lease said automatic clutch progressively as such load increases.

7. In combination, an electric driving motor, a working device driven by such motor, a feeding device, a gearing through which said feeding device is driven, said gearing including two members between which said driving motor produces a reaction, one of said members being connected 10 to said feeding device, a stationary part, an automatic clutch and a manually-controlled clutch one of which acts through the other to connect parts of said gearing through the other of said two members to the stationary 15 part and both of which must be set to produce the reaction, and an electro-magnet connected in series with said motor and tending to release said automatic clutch.

8. In combination, an electric driving 20 motor, a working device driven by such motor, a feeding device, a gearing through which said feeding device is driven, said gearing including two members between which said driving motor produces a reaction, one of said members being connected 25 to said feeding device, a stationary part, an automatic clutch acting to connect parts of said gearing through said second member to the stationary part, and an electro- 30 magnet connected in series with said motor and tending to release said automatic clutch.

9. In combination, a driving motor, a working device driven from such motor, a feeding device, two sun gears of different 35 size, one of said sun gears being connected to said feeding device, planet gears meshing respectively with said two sun gears and rotatable together, a stationary part, a connection from said driving motor for 40 driving said planet gears around the axis of said sun gears, an automatic clutch for connecting said stationary part through said second sun gear to the remainder of the aforesaid gearing to produce a driving reaction 45 for the feeding device to work against, a manually operated device for reducing the reaction effect produced by said automatic clutch, and means for controlling the setting of said automatic clutch by the load on said 50 driving motor.

10. In combination, a driving motor, a working device driven from such motor, a feeding device, two sun gears of different size, one of said sun gears being connected 55 to said feeding device, planet gears meshing respectively with said two sun gears and rotatable together, a stationary part, a connection from said driving motor for driving 60 said planet gears around the axis of said sun gears, an automatic clutch for connecting said stationary part through said second sun gear to the remainder of the aforesaid gearing to produce a driving reaction 65 for the feeding device to work against, and means for controlling the setting of 70 such load increases.

said automatic clutch by the load on said driving motor.

11. In combination, a driving motor, a working device driven from such motor, a feeding device, two sun gears of different 70 size, one of said sun gears being connected to said feeding device, planet gears meshing respectively with said two sun gears and rotatable together, a stationary part, a connection from said driving motor for driving 75 said planet gears around the axis of said sun gears, an automatic clutch for connecting said stationary part through said second sun gear to the remainder of the aforesaid gearing to produce a driving reaction 80 for the feeding device to work against, a manually operated device for reducing the reaction effect produced by said automatic clutch, and means for releasing said automatic clutch progressively as the load 85 on said driving motor increases.

12. In combination, a driving motor, a working device driven from such motor, a feeding device, two sun gears of different 90 size, one of said sun gears being connected to said feeding device, planet gears meshing respectively with said two sun gears and rotatable together, a stationary part, a connection from said driving motor for driving 95 said planet gears around the axis of said sun gears, an automatic clutch for connecting said stationary part through said second sun gear to the remainder of the aforesaid gearing to produce a driving reaction 100 for the feeding device to work against, and means for releasing said automatic clutch progressively as the load on said driving motor increases.

13. In combination, a driving motor, a working device driven from such motor, a feeding device, two sun gears of different 105 size, one of said sun gears being connected to said feeding device, planet gears meshing respectively with said two sun gears and rotatable together, a stationary part, a connection from said driving motor for driving 110 said planet gears around the axis of said sun gears, an automatic clutch for connecting said stationary part through said second sun gear to the remainder of the aforesaid gearing 115 to produce a driving reaction for the feeding device to work against, a manually operated device for reducing the reaction effect produced by said automatic clutch, and an electro-magnet which is energized substantially in proportion to the load on the driving motor and acts on said automatic clutch to release it progressively as such load increases.

14. In combination, a driving motor, a working device driven from such motor, a feeding device, two sun gears of different size, one of said sun gears being connected to said feeding device, planet gears meshing 125 respectively with said two sun gears and ro- 130

- tatable together, a stationary part, a connection from said driving motor for driving said planet gears around the axis of said sun gears, an automatic clutch for connecting said stationary part through said second sun gear to the remainder of the aforesaid gearing to produce a driving reaction for the feeding device to work against, and an electro-magnet which is energized substantially in proportion to the load on the driving motor and acts on said automatic clutch to release it progressively as such load increases. 5

15. In combination, an electric driving motor, a working device driven from such motor, a feeding device, two sun gears of different size, one of said sun gears being connected to said feeding device, planet gears meshing respectively with said two sun gears and rotatable together, a stationary part, a connection from said driving motor for driving said planet gears around the axis of said sun gears, an automatic clutch for connecting said stationary part through said second sun gear to the remainder of the aforesaid gearing to produce a driving reaction for the feeding device to work against, a manually operated device for reducing the reaction effect produced by said automatic clutch, and an electro-magnet connected in series with said driving motor and tending to release said automatic clutch. 20

automatic brake and a manual brake acting in tandem on the other of said members, and means for releasing said automatic brake progressively as the load on said driving motor increases.

25. In combination, a rotatable member, a driven gearing including two members between which the driving produces a reaction, one of said two members being connected to said rotatable member, and an automatic brake and a manual brake acting in tandem on the other of said two members.

26. In combination, a driving motor, a working device driven by such motor, a feeding device, a driven gearing including two members between which a reaction is produced by its driving, one of said members being connected to said feeding device, a rotatably mounted brake casing, an automatic brake connecting said brake casing and the other of said two members, a manual brake for controlling the movements of said brake casing, and means controlled by the load on said driving motor for releasing said automatic brake progressively as the load on the driving motor increases.

27. In combination, a rotatable member, a driven gearing including two members between which a reaction is produced by its driving, one of said two members being connected to said rotatable member, a rotatably mounted brake casing, an automatic brake connecting said brake casing and the other of said two members, and a manual brake for controlling the movements of said brake casing.

28. In combination, a rotatable member, a driven gearing including two members between which a reaction is produced by its driving, one of said two members being connected to said rotatable member, a worm wheel driven by the other of said two members, a worm meshing with and driven by said worm wheel, and a releasable brake acting on said worm.

29. In combination, a cutter, a driving motor therefor, a feeding device for feeding said cutter, a variable speed driving connection between said driving motor and said feeding device, an automatic device controlled by the load on the driving motor for varying the speed relationship of the parts in said variable speed driving connection to produce a speed of feeding which varies in inverse sense as such load, and manually operated means for varying such speed relationship to produce any speed of feeding below that at which said automatic device operates.

30. In combination, a cutter, a driving motor therefor, a feeding device for feeding said cutter, a variable speed driving connection between said driving motor and said feeding device, and an automatic device controlled by the load on the driving motor for

varying the speed relationship of the parts in said variable speed driving connection to produce a speed of feeding which varies in inverse sense as such load.

31. In combination, a cutter, a driving motor therefor, a feeding device for feeding said cutter, a driving connection between said motor and said feeding device, said driving connection including a variably releasable friction device and means controlled by the load on the motor for controlling said variably releasable friction device.

32. In combination, a driving motor, a working device driven by such motor, a feeding device, a gearing driven by such driving motor and including two members between which said driving motor produces a reaction, one of said members being connected to said feeding device, a clutch associated with said gearing and controlling the reaction produced between said two members, and means responsive to the load on the working device for controlling said clutch.

33. In combination, a driving motor, a working device driven by such motor, a feeding device, a gearing driven by such driving motor and including two members between which said driving motor produces a reaction, one of said members being connected to said feeding device, a clutch associated with said gearing and controlling the reaction produced between said two members, and an electro-magnetic device which is energized in proportion to the load on said working device and acts to release said clutch progressively as such load increases.

34. In combination, an electric driving motor, a working device driven by such motor, a feeding device, a gearing driven by such driving motor and including two members between which said driving motor produces a reaction, one of said members being connected to said feeding device, a clutch associated with said gearing and controlling the reaction produced between said two members, and an electro-magnet connected in series with said motor and tending to release said clutch.

35. In combination, a driving motor, a feeding device, an element driven by such driving motor, two members between which said element is interposed and produces a reaction, one of said members being connected to said feeding device, and a clutch associated with said gearing and controlling the reaction produced between said two members, said clutch being adjustably releasable to permit any desired slippage.

36. In combination, a driving motor, a feeding device, a gearing through which said feeding device is driven, said gearing including an element driven by said motor

- and two members between which said element is interposed and produces a reaction, one of said members being connected to said feeding device, a stationary part, and 5 6 an adjustably releasable clutch acting to connect parts of said gearing through said second member to the stationary part.
37. In combination, a driving motor, a feeding device, two coaxial gears of different size, one of said coaxial gears being connected to said feeding device, planet gears meshing respectively with said two coaxial gears and rotatable together, a stationary part, a connection from said driving motor 10 15 for driving said planet gears around the axis of said coaxial gears, and an adjustably releasable clutch for connecting said stationary part through said second coaxial gear to the remainder of the aforesaid gearing 20 to produce a driving reaction for the feeding device to work against.
38. In combination, an electric motor, a working device driven thereby, a feeding device operated by said motor to feed said 25 working device to its work, and means controlled by the current taken by said motor for varying the rate of operation of said feeding device to maintain such current substantially constant.
39. In combination, an electric motor, a working device driven thereby, a feeding device, a driving connection interconnecting said driving motor and said feeding device and including two parts which can slip 30 35 relatively to each other to control the relation between the speeds of the driving motor and the feeding device, and means for controlling the slipping of said two parts by the current taken by the motor to vary the 40 ratio of the speeds of the feeding device and the driving motor in inverse sense as such current.
40. In combination, an electric motor, a working device driven thereby, a feeding 45 device, a driving connection interconnecting said driving motor and said feeding device and including two parts which can slip relatively to each other to control the relation between the speeds of the driving motor 50 and the feeding device, and means for controlling the slipping of said two parts by the current taken by the motor.
41. In combination, a cutter, a driving motor therefor, a feeding device for feeding 55 said cutter, said feeding device being driven from said driving motor, and automatic means for operatively disconnecting said feeding device from said driving motor when said cutter strikes an obstruction and 60 thereafter reconnecting the same independently of the movement of said cutter.
42. In combination, a feeding device including a clutch for controlling the operation thereof, a driving motor operatively 65 connected to said feeding device, a working device driven by said motor, and means responsive to the load upon said motor for controlling the connection of said clutch.
43. In combination, an electric driving motor, a working device driven by said motor, a feeding device, means for operating said feeding device from said motor, said means including a friction clutch, a solenoid connected in the armature circuit of said motor, and means controlled by said solenoid for operating said clutch. 70 75
44. In combination, a cutter, a driving motor therefor, a feeding device for feeding said cutter, said feeding device being driven from said motor, and means for controlling the operation of said feeding device by said driving motor normally under manual control and automatically operable when said cutter strikes an obstruction to disconnect said feeding device from said motor and thereafter re-connect the same. 80 85
45. In a mining machine, in combination, an actuating shaft, feeding mechanism including a feed shaft operatively connected with said actuating shaft and having transmission and controlling devices thereon, and cutting mechanism including a shaft arranged transverse to said feed shaft in substantially the vertical plane thereof between certain of the devices thereon, said cutting mechanism shaft being operatively connected with said actuating shaft independently of the connections between said actuating shaft and said feed shaft. 90 95
46. In a mining machine, in combination, an actuating shaft, feeding mechanism including a feed shaft operatively connected with said actuating shaft and having transmission and controlling devices thereon, and cutting mechanism including a shaft arranged transverse to said feed shaft in substantially the vertical plane thereof between certain of the devices thereon, said cutting mechanism shaft having thereon a gear operatively connected with said actuating shaft and dished to receive the transmission devices on said feed shaft. 100 105 110
47. In a mining machine, feeding mechanism comprising a transmission shaft, a feed shaft, a pair of gears on said transmission shaft, a pair of gears on said feed shaft meshing with said first named gears respectively, studs rigidly connecting said last named gears, planet gears rotatably mounted on said studs, and a sun gear on said feed shaft co-operating with said planet gears. 115 120
48. In a mining machine, in combination, a casing, an upright shaft having a bearing in the upper wall of said casing, transmission mechanism within said casing including elements on said shaft, and means for supplying lubricant to said bearing from the exterior of said casing, the uppermost of the elements on said shaft having an upright flange surrounding said bearing for 125 130

retaining lubricant therein while permitting said lubricant to overflow into said casing to lubricate the transmission mechanism therein.

5. 49. In a mining machine, in combination, a casing, transmission mechanism therein including a shaft having a bearing beneath said casing, means for supplying lubricant to said casing to lubricate said transmission mechanism, and an overflow device for conducting excess lubricant from said casing to said bearing.

10 50. In a mining machine, a motor, cutting mechanism operatively connected thereto, feeding mechanism for said cutting mechanism, means for operating said feeding mechanism from said motor, said means including a friction clutch, a manually operable controlling member for said clutch, and means for inhibiting loading of said friction clutch by said manually operable controlling member while permitting the manipulation normally effective to cause loading.

15 51. In a mining machine, a motor, cutting mechanism operatively connected thereto, feeding mechanism for said cutting mechanism, means for operating said feeding mechanism from said motor, said means including a friction clutch, manually operable clutch controlling means, and automatic means responsive to resistance to cutting for inhibiting loading of said clutch by said manually operable means.

20 52. In a mining machine, a motor, cutting mechanism operatively connected thereto, feeding mechanism, means for operating said feeding mechanism from said motor, said means including a friction clutch, manually operable clutch controlling means, and automatic means responsive to resistance to feeding for inhibiting loading of said clutch by said manually operable means.

25 53. In a mining machine, a motor, cutting mechanism operatively connected thereto, feeding mechanism for said cutting mechanism, means for operating said feeding mechanism from said motor, said means including a friction clutch, manually operable clutch controlling means, and means responsive to resistance to cutting for releasing said clutch despite reverse operation of said manually operable means.

30 54. In a mining machine, a motor, cutting mechanism operatively connected thereto, feeding mechanism for said cutting mechanism, means for operating said feeding mechanism from said motor, said means including a friction clutch, manually operable clutch controlling means, and means responsive to resistance to feeding or releasing said clutch despite reverse operation of said manually operable means.

35 55. In a mining machine, a machine frame, a motor thereon, a feed operating member thereon, variable speed transmission

mechanism driven by said motor and operatively connected between the same and said feed operating member, a closed lubricant containing casing enclosing said variable speed transmission mechanism, and a cutter chain driving sprocket operatively connected to said transmission mechanism and located outside of said casing.

40 56. In a mining machine, a machine frame, a motor thereon, a feed operating member thereon, transmission mechanism driven by said motor and operatively connected between the same and said feed operating member, a closed lubricant containing casing enclosing said transmission mechanism, and cutting mechanism including a cutter chain driving sprocket operatively connected to said transmission mechanism and located outside of said casing.

45 57. In a mining machine, a machine frame, a motor thereon, a feed operating member thereon, variable speed transmission mechanism driven by said motor and operatively connected between the same and said feed operating member, a closed lubricant containing casing enclosing said variable speed transmission mechanism, a cutter chain driving sprocket operatively connected to said motor and located outside of said casing, and means for supplying lubricant from said casing to said cutter chain sprocket.

50 58. In a mining machine, a machine frame, a motor thereon, a feed operating member thereon, transmission mechanism driven by said motor and operatively connected between the latter and said feed operating member, a closed lubricant containing casing enclosing said transmission mechanism, cutting mechanism including a cutter chain driving sprocket driven by said transmission mechanism and located outside of said casing, and means for supplying lubricant from said casing to said cutter chain sprocket.

55 59. In a mining machine, a machine frame, feeding mechanism thereon including a feed operating member rotatable on a transverse axis, a horizontal motor on said frame rotatable on an axis extending longitudinally thereof, operative connections between said motor and said feed operating member comprising transmission mechanism, a lubricant containing casing enclosing said transmission mechanism, cutting mechanism including a cutter chain driving sprocket driven by said transmission mechanism and located outside of said casing, and means for supplying lubricant from said casing to said cutter chain sprocket.

60 60. In a mining machine, a machine frame, feeding mechanism thereon including a feed operating member rotatable on a transverse axis, a horizontal motor on said frame rotatable on an axis extending longi-

- tudinally thereof, operative connections between said motor and said feed operating member comprising variable speed transmission mechanism, a lubricant containing casing enclosing said variable speed transmission mechanism, cutting mechanism including a cutter chain driving sprocket driven by said transmission mechanism and located outside of said casing, and means 10 for supplying lubricant from said casing to said cutter chain sprocket.
61. In a mining machine, feeding mechanism including a feed operating member rotatable on a transverse axis and a horizontal motor rotatable on a longitudinal axis, a plurality of transversely disposed feed operating shafts, operative connections between one of said shafts and said feed operating member and between the other shaft 20 and said motor, variable speed reduction gearing operatively connected between said shafts, a lubricant containing casing enclosing said gearing, and cutting mechanism driven by said motor including a cutter chain sprocket located beneath said casing and receiving lubricant therefrom.
62. A room and pillar machine comprising a machine frame, a horizontal motor thereon having an armature shaft rotatable on an axis extending longitudinally of said frame, an upstanding driving member carried on said frame and disposed in rear of said motor, driving connections between the rear end of said motor and said member 30 comprising a pinion on said shaft and a gear meshing therewith and carried on said member, cutting mechanism including a cutter chain driving sprocket in a plane beneath said motor, operative connections between said motor, and said sprocket and said motor whereby the former is rotated, and mechanism for feeding said frame bodily laterally along a mine face including a feed operating member on said frame, and driving connections for said feed operating member including a worm on said upstanding member.
63. In a mining machine, a machine frame, a horizontal motor rotatable thereon on an axis longitudinally of said frame, an upright driving member carried on said frame in rear of said motor, operative connections between said motor and said member cutting mechanism including, a cutter chain driving sprocket in a plane beneath said motor and operatively connected to said member, a rotatable worm fixed on said member below the connection to the latter of said first mentioned operative connections, a worm gear rotatable by said worm, flexible feeding mechanism for feeding said frame bodily laterally along a mine face including a feed operating member on said frame, and a feed operating member on said frame and variable speed transmission mechanism between said feed operating member and said worm gear.
64. In a mining machine, a machine frame, a horizontal motor thereon rotatable on an axis extending longitudinally of said frame, an upright driving member carried on said frame in rear of said motor, operative connections between said motor and said member, cutting mechanism including a cutter chain driving sprocket in a plane beneath said motor and operatively connected to said member, a rotatable worm fixed on said member below the connection to the latter of said first mentioned operative connections, a transverse shaft in rear of said member, a worm gear rotatable by said worm and disposed on said transverse shaft, flexible feeding mechanism for feeding said frame bodily laterally along a mine face including a feed operating member on said frame, and variable speed transmission mechanism between said feed operating member and said shaft.
65. In a mining machine, a machine frame, a horizontal motor thereon rotatable on an axis extending longitudinally of said frame, an upright driving member carried on said frame in rear of said motor, operative connections between said motor and said member, cutting mechanism including a cutter chain driving sprocket operatively connected to said member, a rotatable worm fixed on said member below the connection to the latter of said first mentioned operative connections, a worm gear rotatable by said worm and disposed on a transverse axis, flexible feeding mechanism for feeding said frame bodily laterally along a mine face including a feed operating member on said frame, and variable speed transmission mechanism between said feed operating member and said worm gear including a plurality of transversely extending members, and reduction gearing operatively connected between said members.
66. In a mining machine, a machine frame, a horizontal motor thereon rotatable on an axis extending longitudinally of said frame, an upstanding driving member carried on said frame and disposed in rear of said motor, driving connections between the rear end of said motor and the upper end of said member, cutting mechanism including a cutter chain driving sprocket, driving connections between said sprocket and the lower end of said member, flexible feeding mechanism for feeding said frame bodily laterally along a mine face including a feed operating member on said frame, and driving connections thereto operatively connected to said upstanding member at a point above the connection of one of said driving connections thereto and below the connection of the other of said driving connections thereto.
67. In a mining machine, a machine frame, a horizontal motor thereon rotatable

on an axis extending longitudinally of said frame, an upstanding driving member carried on said frame and disposed in rear of said motor, driving connections between the rear end of said motor and the upper end of said member, cutting mechanism including a cutter chain driving sprocket, driving connections between said sprocket and the lower end of said member, flexible feeding mechanism for feeding said frame bodily laterally along a mine face including a feed operating member on said frame, and driving connections therefor operatively connected to said upstanding member at a point below the connection of one of said driving connections thereto.

63. In a mining machine, a machine frame, a horizontal motor thereon rotatable on an axis extending longitudinally of said frame, an upstanding driving member disposed in rear of said motor, speed reducing driving connections between the rear end of said motor and the upper end of said member, cutting mechanism including a cutter chain driving sprocket, operative connections between the same and the lower end of said member, flexible feeding mechanism for feeding said frame bodily laterally along a mine face including a feed operating member on said frame rotatable on a transverse axis, and driving connections for said feed operating member including a plurality of transverse members, a worm and worm gear between one of the same and said upstanding member, and variable speed gearing between said members.

69. In a mining machine, a machine frame, a horizontal motor thereon rotatable on an axis extending longitudinally of said frame, an upstanding driving member carried on said frame and disposed in rear of said motor, speed reducing driving connections between the rear end of said motor and said member, cutting mechanism including a cutter chain driving sprocket, operative connections between the latter and said member, flexible feeding means for feeding said frame bodily laterally along a mine face including a feed operating member rotatable on a transverse axis, and driving connections for said feed operating member including a plurality of transverse members, a worm and worm gear between one of the same and said upstanding member, plural predetermined speed gearing between said transverse members, and reduction gearing between the other transverse members and said feed operating member.

70. A room and pillar mining machine 69 slideable on its bottom including a motor, an upstanding member longitudinally spaced from said motor, a cutter chain driving sprocket longitudinally spaced from said member, lateral feeding mechanism includ- 65 ing a member disposed transversely direct-

ly above said sprocket, and means for driving both said sprocket and said transverse member from said motor including driving means coaxial with said upstanding member.

71. A room and pillar mining machine 70 slideable on its bottom including a motor, an upstanding member longitudinally spaced from said motor, a cutter chain driving sprocket longitudinally spaced from said member and more remote than said member from said motor, lateral feeding mechanism including a member disposed transversely above said sprocket, and means for driving both said sprocket and said transverse member from said motor including a bevel gear 80 carried on said upstanding member.

72. A room and pillar mining machine 85 slideable on its bottom including a motor, an upstanding member longitudinally spaced from said motor, a cutter chain driving sprocket longitudinally spaced from said member, means for rotating said sprocket from said motor including a member coaxial with said upstanding member, and lateral feeding mechanism likewise driven by said motor including a member disposed with its axis in a horizontal plane above said sprocket and in a position in such plane such that its vertical projection substantially bisects said sprocket.

73. A room and pillar mining machine 90 slideable on its bottom including cutter driving mechanism including a cutter chain sprocket and a gear coaxial with and of greater diameter than said sprocket and accessible from one end of the machine, lateral feeding mechanism including a transversely extending member disposed above said gear, a motor, and means for driving both said mechanisms therefrom including a bevel gear driven by said motor.

74. A room and pillar mining machine 100 slideable on a mine bottom comprising a motor, an upstanding member in rear of said motor, a cutter chain driving sprocket in rear of said member, downwardly facing bevel gearing on said member driven by said motor, and spur gearing driven by said bevel gearing and driving said cutter chain sprocket.

75. A room and pillar mining machine 110 slideable on a mine bottom comprising a motor disposed longitudinally thereof, an upstanding member in rear of said motor, a cutter chain driving sprocket in rear of said member, bevel gearing on said member driven by said motor, and spur gearing driven by said bevel gearing and driving said cutter chain sprocket including a large 120 spur gear coaxial with said sprocket and adapted to be moved into mesh with and operatively engage a truck driving element.

76. A room and pillar mining machine 125 slideable on its bottom on a mine bottom comprising a motor, an upstanding member in

- rear thereof, a cutter chain driving sprocket in rear of said member, sprocket driving connections driven by said motor including a member carried on said upstanding member and a hollowed-out gear, and means for feeding the machine laterally likewise driven by said motor and disposed above said gear and having a portion extending into the hollow therein.
77. A room and pillar mining machine including a machine frame, a motor thereon having its armature shaft rotatable on an axis extending longitudinally of said frame, an upstanding member carried on said frame in rear of said motor, cutting mechanism including a cutter chain driving sprocket, feeding mechanism for feeding said frame bodily laterally along a mine face including a feed operating member rotatable on a transverse axis, a rotatable gear disposed on said upstanding member, operative connections between the same and said feed operating member, and means for rotating said sprocket and said rotatable gear by power from said motor including a bevel pinion on said armature shaft and a bevel gear meshing with said pinion and disposed on said upstanding member above said rotatable gear.
78. A room and pillar mining machine including a machine frame, a motor thereon having its armature shaft rotatable on an axis extending longitudinally of said frame, an upstanding member carried on said frame in rear of said motor, cutting mechanism including a cutter chain driving sprocket, feeding mechanism for feeding said frame bodily laterally along a mine face including a feed operating member rotatable on a transverse axis, a rotatable gear disposed on said upstanding member, operative connections between the same and said feed operating member, and means for rotating said sprocket and said rotatable gear by power from said motor including a gear member meshing with said last mentioned gear member and disposed on said upstanding member in a position above said rotatable gear.
79. A room and pillar mining machine including a machine frame, a motor thereon having its armature shaft rotatable on an axis extending longitudinally of said frame, an upstanding member carried on said frame in rear of said motor, cutting mechanism including a cutter chain driving sprocket, feeding mechanism for feeding said frame bodily laterally along a mine face including a feed operating member rotating on a horizontal axis and a rotatable gear disposed on said upstanding member and operatively connected to said feed operating member, and means for rotating said sprocket and said rotatable gear including a pinion on said armature shaft and a gear meshing with said pinion and disposed on said upstanding member in position overlying said rotatable gear.
80. A room and pillar mining machine including a machine frame, a motor thereon having its armature shaft rotatable on an axis extending longitudinally of said frame, an upstanding member carried on said frame in rear of said motor, cutting mechanism including a cutter chain driving sprocket, feeding mechanism for feeding said frame bodily laterally along a mine face including a feed operating member and a rotatable worm disposed on said upstanding member and operatively connected to said feed operating member, and means for rotating said sprocket and said worm by power from said motor including a pinion on said armature shaft and a gear meshing with said pinion and disposed on said member above said worm.
81. A room and pillar mining machine including a machine frame, a motor thereon having its armature shaft rotatable on an axis extending longitudinally of said frame, an upstanding member carried on said frame in rear of said motor, cutting mechanism including a cutter chain driving sprocket, feeding mechanism for feeding said frame bodily laterally along a mine face including a feed operating member, a rotatable worm disposed on said upstanding member, and operative connections between said worm and said feed operating member including a worm gear rotatable on a transverse axis, and means for rotating said sprocket and said worm by power from said motor including a pinion on said armature shaft and a gear meshing with said pinion and disposed on said member above said worm and worm gear.
82. A room and pillar mining machine including a machine frame, a horizontal motor thereon rotatable on an axis extending longitudinally of said frame, cutting mechanism thereon including a cutter chain driving sprocket, means for driving said sprocket from one end of said motor including a horizontally disposed bevel gear, mechanism for feeding said frame bodily laterally along a mine face including a feed operating member rotatable on a transverse axis, and speed reducing driving connections between said bevel gear and said feed operating member including a plurality of operatively connected transverse members one of which is disposed beneath the plane of said bevel gear.
83. A room and pillar mining machine including a machine frame, a horizontal motor thereon rotatable on an axis extending longitudinally of said frame, cutting mechanism including a cutter chain driving sprocket, means for driving said sprocket from one end of said motor including a horizontally disposed bevel gear, mechanism for feeding said frame bodily laterally along a

mine face including a feed operating member rotatable on a transverse axis, and speed reducing driving connections between said bevel gear and said feed operating member 6 including a plurality of longitudinally spaced transverse members each disposed below the plane of said bevel gear.

84. A room and pillar mining machine including a machine frame, a horizontal 10 motor thereon rotatable on an axis extending longitudinally of said frame, cutting mechanism thereon including a cutter chain driving sprocket, means for driving said sprocket from one end of said motor, mechanism 15 for feeding said frame bodily laterally along a mine face including a feed operating member rotatable on a transverse axis, and operative connections between said driving means and said feed operating member 20 operative to rotate the latter at a plurality of predetermined speeds including a plurality of transverse members and variable speed transmission mechanism between said transverse members.

85. In a mining machine, a machine frame, a horizontal motor thereon rotatable on an axis extending longitudinally of said frame, cutting mechanism thereon including a cutter chain driving sprocket, means for driving 25 said sprocket from one end of said motor, feeding mechanism for feeding said frame bodily laterally along a mine face including a feed operating member, and operative connections between said driving 30 means and said feed operating member including a pair of transverse members, one comprising the sole driving member and connected to said driving means and the other comprising the sole driven member 35 and having a direct geared connection with said feed operating member, and speed reduction mechanism between said transverse members carried by said members.

86. In a mining machine, a machine frame, a horizontal motor thereon rotatable on an axis extending longitudinally of said frame, cutting mechanism thereon including a cutter chain driving sprocket, means for driving 40 said sprocket from the rear end of said motor including a bevel gear rotatable on an upright axis, mechanism for feeding said frame bodily laterally along a mine face including a feed operating member, and operative connections between said bevel gear 45 and said feed operating member including a pair of transverse members, one directly connected to said driving means and the other directly geared to said feed operating member, and speed reduction mechanism 50 between said transverse members having its elements rotatable about the axis of one or the other thereof.

87. In a mining machine, a machine frame, a horizontal motor thereon rotatable 55 on an axis extending longitudinally of said

frame, cutting mechanism thereon including a cutter chain driving sprocket, means for driving said sprocket from the rear end of said motor including a bevel gear rotatable on an upright axis in a position 70 above the axis of rotation of the motor, mechanism for feeding said frame bodily laterally along a mine face including a feed operating member, and operative connections between said bevel gear and said feed 75 operating member including a plurality of transverse members, one connected for driving by said bevel gear and the other connected to said feed operating member and one of said members extending only part 80 way across said frame, and speed reducing mechanism between said members.

88. In a mining machine, a machine frame, a horizontal motor thereon rotatable on an axis extending longitudinally of said frame, cutting mechanism thereon including a cutter chain driving sprocket, means for driving 85 said sprocket from the rear end of said motor, mechanism for feeding said frame bodily laterally along a mine face 90 including a feed operating member, and operative connections between said driving means and said feed operating member including a pair of transverse members, one comprising the main driving member and connected to said driving means and the other comprising the main driven member 95 and geared directly to said feed operating member, and speed reduction mechanism between said transverse members having in- 100 termeshing elements thereof concentric with each of said members.

89. In a mining machine, a machine frame, a horizontal motor thereon rotatable on an axis extending longitudinally of said frame, cutting mechanism thereon including a cutter chain driving sprocket, means for driving said sprocket from the rear end of said motor, mechanism for feeding said frame bodily laterally along a mine face 105 including a feed operating member, and speed reducing connections between said driving means and said feed operating member including a plurality of transverse members, and power transmitting connections 110 therebetween operative to provide a plurality of different definite speeds.

90. In a mining machine, a machine frame, a horizontal motor thereon rotatable on an axis extending longitudinally of said frame, cutting mechanism thereon including a cutter chain driving sprocket, means for driving said sprocket from the rear end of said motor, mechanism for feeding said frame bodily laterally along a mine face 115 including a feed operating member, and operative connections between said driving means and said feed operating member including a plurality of transverse members, one connected to said driving means and 120

one connected to said driving means and 125

the other connected to said feed operating member, and variable speed transmission mechanism between said transverse members operative to drive said feed operating member at a plurality of predetermined speeds.

91. In a mining machine, a machine frame, a horizontal motor thereon rotatable on an axis extending longitudinally of said frame, cutting mechanism thereon including a cutter chain driving sprocket, means for driving said sprocket from the rear end of said motor including a bevel gear, mechanism for feeding said frame bodily laterally along a mine face, including a feed operating drum rotatable on a transverse axis, operative connections between said bevel gear and said drum including a plurality of transverse members at least one of which is disposed below the plane of said gear, speed reduction gearing between said members, and drum driving gearing comprising a pinion on one of said members and a larger meshing gear carried by said drum.

25 92. In a mining machine, a machine frame, a horizontal motor thereon rotatable on an axis extending longitudinally of said frame, cutting mechanism thereon including a cutter chain driving sprocket, means for driving said sprocket from the rear end of said motor including a bevel gear, feeding mechanism including a feed operating member rotatable on a transverse axis, operative connections between said driving means and said feed operating member including an upright rotatable worm below said bevel gear, a worm gear meshing with said worm, a transverse member carrying said worm gear, a second transverse member operatively connected to said feed operating member, and reduction mechanism between said transverse members.

30

35

40

93. In a mining machine, a machine frame, a horizontal motor thereon rotatable on an axis extending longitudinally of said frame, cutting mechanism thereon including a cutter chain driving sprocket, means for driving said sprocket from the rear end of said motor including a bevel gear, feeding mechanism including a feed operating member rotatable on a transverse axis, operative connections between said driving means and said feed operating member including an upright rotatable worm, a worm gear meshing therewith, a transverse member carrying said worm gear, a second transverse member carrying a pinion directly driving said feed operating member, and reduction mechanism between said transverse members having intermeshing elements thereof concentric with each of said members.

94. In a mining machine, a machine frame, a horizontal motor thereon rotatable on an axis extending longitudinally of said frame, cutting mechanism thereon including a cut-

ter chain driving sprocket, means for driving said sprocket from the rear end of said motor including a bevel gear, feeding mechanism including a feed operating member rotatable on a transverse axis, operative connections between said driving means and said feed operating member including an upright rotatable worm disposed below said bevel gear, a worm gear meshing therewith, a transverse worm gear carrying shaft, an adjacent second transverse shaft operatively connected to said feed operating member, one of said shafts being a stub shaft, and speed reduction mechanism between said transverse shafts.

95. In a mining machine, a machine frame, a horizontal motor thereon rotatable on an axis extending longitudinally of said frame, cutting mechanism thereon including a cutter chain driving sprocket, means for driving the latter from the rear end of said motor including a bevel gear, feeding mechanism including a feed operating member rotatable on a transverse axis and carrying a coaxial gear on its periphery, operative connections between said bevel gear and said feed operating member including an upright rotatable worm disposed below said bevel gear, a worm gear meshing therewith, a transverse member carrying said worm gear, a second transverse member carrying a pinion meshing with the gear on said feed operating member, and speed reduction mechanism between said transverse members 85 90 95

96. In a mining machine, a machine frame, a horizontal motor thereon rotatable on an axis extending longitudinally of said frame, cutting mechanism thereon including a cutter chain driving sprocket, means for driving the latter from the rear end of said motor including a bevel gear, feeding mechanism including a feed operating member rotatable on a transverse axis and carrying a coaxial gear on its periphery, and operative connections between said bevel gear and said feed operating member including an upright rotatable worm, a worm gear meshing therewith, a transverse member carrying said worm gear, a second transverse member carrying a pinion meshing with the gear on said feed operating member, and driving connections between said transverse members having provision for controlling the rate of rotation of said feed operating member and including a frictional clutch. 105 110 115 120

97. In a mining machine, a machine frame, a horizontal motor thereon rotatable on an axis extending longitudinally of said frame, cutting mechanism thereon including a cutter chain driving sprocket, means for driving the latter from the rear end of said motor including a bevel gear, feeding mechanism including a feed operating member rotatable on a transverse axis, and operative connections between said member and said 125
130

driving means including an upright rotatable worm below said bevel gear, a worm gear meshing therewith, a transverse member carrying said worm gear, a second transverse member operatively connected to said feed operating member, and variable speed transmission mechanism between said transverse members whereby said feed operating member may be rotated at a plurality of predetermined speeds.

98. In a mining machine, a machine frame, a horizontal motor thereon rotatable on an axis extending longitudinally of said frame, cutting mechanism including a cutter chain driving sprocket, means for driving the latter from the rear end of said motor including a bevel gear, feeding mechanism including a feed operating member rotatable on a transverse axis, operative connections between said member and said driving means including an upright rotatable worm below said bevel gear, a worm gear meshing therewith, a transverse member carrying said worm gear, a second transverse member operatively connected to said feed operating member, and transmission mechanism between said transverse members including a friction clutch and whereby said feed operating member may be rotated at a plurality of speeds.

99. In a mining machine, a machine frame, a horizontal motor thereon rotatable on an axis extending longitudinally of said frame, cutting mechanism including a cutter chain driving sprocket, means for driving the latter from the rear end of said motor including a bevel gear rotatable on an upstanding axis in rear of said motor, feeding mechanism including a feed operating member rotatable on a transverse axis, and operative connections between said feed operating member and said bevel gear including a rotatable worm below said bevel gear, a transverse shaft in rear of said worm, a rotatable worm gear on said shaft, a second transverse shaft operatively connected with said feed operating member, one of said shafts being a relatively short shaft, and reduction mechanism carried on said shafts between said feed operating member and said worm gear.

100. In a mining machine, a machine frame, a horizontal motor thereon rotatable on an axis extending longitudinally of said frame, cutting mechanism including a cutter chain driving sprocket, means for driving the latter from the rear end of said motor including a bevel gear rotatable on an upstanding axis in rear of said motor, feeding mechanism including a feed operating member rotatable on a transverse axis, and operative connections between said feed operating member and said bevel gear including a rotatable worm below said bevel gear, a transverse shaft in rear of said worm,

rotatable worm gear on said shaft, a second transverse shaft operatively connected with said feed operating member, one of said shafts being a relatively short shaft, and variable speed transmission mechanism carried on said shafts between said feed operating member and said worm gear.

101. In a mining machine, a machine frame, a horizontal motor thereon rotatable on an axis extending longitudinally of said frame, cutting mechanism including a cutter chain driving sprocket, means for driving the latter from the rear end of said motor including a bevel gear rotatable on an upstanding axis in rear of said motor, feeding mechanism including a feed operating member rotatable on a transverse axis, and operative connections between said feed operating member and said bevel gear including a rotatable worm below said bevel gear, a transverse shaft in rear of said worm, a rotatable worm gear on said shaft, a second transverse shaft operatively connected with said feed operating member, one of said shafts being a jack shaft, and transmission mechanism for driving said feed operating member at different speeds operatively connected to said shafts and including a friction clutch and reduction mechanism carried on said shafts and having intermeshing elements concentric with one or the other thereof.

102. A room and pillar mining machine including a motor having its armature shaft rotatable on an axis extending longitudinally of the machine, cutting mechanism including a cutter chain driving sprocket, a driving gear therefor coaxial therewith, feeding mechanism for feeding said machine bodily laterally along a mine face including a feed operating member, a worm wheel and planetary driving connections between said worm wheel and feed operating member, said planetary gearing including coaxial gears and means meshing with the latter and orbitally moving with respect thereto to produce a reaction, and means for rotating said cutter chain driving sprocket driving gear and said worm wheel by power from said motor including a driving pinion on said armature shaft, a gear meshing therewith and driven thereby, a shaft on which said last mentioned gear is fixed, a worm on said shaft engaging said worm wheel, and a pinion on said shaft engaging said cutter chain driving sprocket driving gear.

103. A room and pillar mining machine including a motor having its armature shaft rotatable on an axis extending longitudinally of the machine, cutting mechanism including a cutter chain driving sprocket, a driving gear therefor coaxial therewith, feeding mechanism for feeding said machine bodily laterally along a mine face including a feed operating member, a

- worm wheel and speed changing planetary driving connections between said worm wheel and feed operating member, and means for rotating said cutter chain driving sprocket driving gear and said worm wheel including a driving pinion on said armature shaft, a gear meshing therewith and driven thereby, a shaft on which said last mentioned gear is fixed, a worm on said shaft engaging said worm wheel, and a pinion on said shaft engaging said cutter chain driving sprocket driving gear, said worm being between said gear and pinion on said shaft.
104. A room and pillar mining machine including a motor having its armature shaft rotatable on an axis extending longitudinally of the machine, cutting mechanism including a cutter chain driving sprocket, a driving gear therefor coaxial therewith, feeding mechanism for feeding said machine bodily laterally along a mine face including a feed operating member, a worm wheel and friction controlled planetary driving connections between said worm wheel and feed operating member, and means for rotating said cutter chain driving sprocket driving gear and said worm wheel including a driving pinion on said armature shaft, a gear meshing therewith and driven thereby, a shaft on which said last mentioned gear is fixed, a worm on said shaft engaging said worm wheel, and a pinion on said shaft engaging said cutter chain driving sprocket driving gear, said worm being between said gear and pinion on said shaft.
105. A room and pillar mining machine including a motor having its armature shaft rotatable on an axis extending longitudinally of the machine, cutting mechanism including a cutter chain driving sprocket, a driving gear therefor coaxial therewith, feeding mechanism for feeding said machine bodily laterally along a mine face including a feed operating member, a worm wheel, planetary driving connections between said worm wheel and feed operating member and clutch mechanism coaxial with said worm wheel, and means for rotating said cutter chain driving sprocket driving gear and said worm wheel by power from said motor including a driving pinion on said armature shaft, a gear meshing therewith and driven thereby, a shaft on which said last mentioned gear is fixed, a worm on said shaft engaging said worm wheel, and a pinion on said shaft engaging said cutter chain driving sprocket driving gear.
106. A room and pillar mining machine including a motor having its armature shaft rotatable on an axis extending longitudinally of the machine, cutting mechanism including a cutter chain driving sprocket, a driving gear therefor coaxial therewith, feeding mechanism for feeding said machine bodily laterally along a mine face including a feed operating member, a worm wheel, planetary driving connections between said worm wheel and feed operating member, and clutch mechanism coaxial with said worm wheel and feed operating member, and clutch mechanism coaxial with said planetary driving connections, and means for rotating said cutter chain driving sprocket driving gear and said worm wheel including a driving pinion on said armature shaft, a gear meshing therewith and driven thereby, a shaft on which said last mentioned gear is fixed, a worm on said shaft engaging said worm wheel, and a pinion on said shaft engaging said cutter chain driving sprocket driving gear.
107. A room and pillar mining machine including a motor having its armature shaft rotatable on an axis extending longitudinally of the machine, cutting mechanism including a cutter chain driving sprocket, a driving gear therefor coaxial therewith, feeding mechanism for feeding said machine bodily laterally along a mine face including a feed operating member, a worm wheel, planetary driving connections coaxial with said worm wheel between said worm wheel and feed operating member, and clutch mechanism including a member reciprocable axially of said worm wheel and planetary driving connections, and means for rotating said cutter chain driving sprocket driving gear and said worm wheel including a driving pinion on said armature shaft, a gear meshing therewith and driven thereby, a shaft on which said last mentioned gear is fixed, a worm on said shaft engaging said worm wheel, and a pinion on said shaft engaging said cutter chain driving sprocket driving gear, said worm being between the gear and pinion on said shaft.
108. A room and pillar mining machine including a motor having its armature shaft rotatable on an axis extending longitudinally of the machine, cutting mechanism including a cutter chain driving sprocket, a driving gear therefor coaxial therewith, feeding mechanism for feeding said machine bodily laterally along a mine face including a feed operating member, a worm wheel, and planetary driving connections between said worm wheel and feed operating member, said planetary connections including a plurality of orbitally moving gears traversing their orbits at equal angular rates and having pitch line speeds bearing a predetermined ratio to each other and a plurality of mutually coaxial gears with which said orbitally moving gears cooperate, one of which is adapted to constitute a reaction member, and means for rotating said cutter chain driving sprocket driving gear.

- Driving sprocket driving gear and said worm wheel including a driving pinion on said armature shaft, a gear meshing therewith and driven thereby, a shaft on which said last mentioned gear is fixed, a worm on said shaft engaging said worm wheel, and a pinion on said shaft engaging said cutter chain driving sprocket driving gear.
109. A room and pillar mining machine including a motor having its armature shaft rotatable on an axis extending longitudinally of the machine, cutting mechanism including a cutter chain driving sprocket, a driving gear therefor coaxial therewith, feeding mechanism for feeding said machine bodily laterally along a mine face including a feed operating member, a worm wheel and planetary driving connections between said worm wheel and feed operating member, said planetary connections including a plurality of orbitally moving gears traversing their orbits at equal angular rates and having pitch line speeds bearing a predetermined ratio to each other and a plurality of mutually coaxial gears with which said orbitally moving gears cooperate, one of which is adapted to constitute a reaction member, frictional controlling means therefor, and means for rotating said cutter chain driving sprocket driving gear and said worm wheel including a driving pinion on said armature shaft, a gear meshing therewith and driven thereby, a shaft on which said last mentioned gear is fixed, a worm on said shaft engaging said worm wheel, and a pinion on said shaft engaging said cutter chain driving sprocket driving gear.
110. A room and pillar mining machine including a motor having its armature shaft rotatable on an axis extending longitudinally of the machine, cutting mechanism including a cutter chain driving sprocket, a driving gear therefor coaxial therewith, feeding mechanism for feeding said machine bodily laterally along a mine face including a feed operating member, a worm wheel and planetary driving connections between said worm wheel and feed operating member, said planetary connections including a plurality of orbitally moving gears traversing their orbits at equal angular rates and having pitch line speeds bearing a predetermined ratio to each other and a plurality of mutually coaxial gears with which said orbitally moving gears cooperate, one of which is adapted to constitute a reaction member, controlling means therefor including friction mechanism and jaw clutch mechanism, and means for rotating said cutter chain driving sprocket driving gear and said worm wheel including a driving pinion on said armature shaft, a gear meshing therewith and driven thereby, a shaft on which said last mentioned gear is fixed, a worm on said shaft engaging said worm wheel, and a pinion on said shaft engaging said cutter chain driving sprocket driving gear and said worm wheel engaging said cutter chain driving sprocket driving gear.
111. A room and pillar mining machine including a motor having its armature shaft rotatable on an axis extending longitudinally of the machine, cutting mechanism including a cutter chain driving sprocket, a driving gear therefor coaxial therewith, feeding mechanism for feeding said machine bodily laterally along a mine face at a cutting speed or for feeding the same at a higher speed including a feed operating member, a worm wheel, and planetary driving connections between said worm wheel and feed operating members, said planetary connections including a plurality of orbitally moving gears traversing their orbits at equal angular rates and having pitch line speeds bearing a predetermined ratio to each other and a plurality of mutually coaxial gears with which said orbitally moving gears cooperate, one of which is adapted to constitute a reaction member, and mechanism controlling the operation of said feeding mechanism including a plurality of jaw clutches and a frictional controlling mechanism, and means for rotating said cutter chains driving sprocket driving gear and said worm wheel including a driving pinion on said armature shaft, a gear meshing therewith and driven thereby, a shaft on which said last mentioned gear is fixed, a worm on said shaft engaging said worm wheel, and a pinion on said shaft engaging said cutter chain driving sprocket driving gear.
112. A room and pillar mining machine including a motor having its armature shaft rotatable on an axis extending longitudinally of the machine, cutting mechanism including a cutter chain driving sprocket, a driving gear therefor coaxial therewith, feeding mechanism for feeding said machine bodily laterally along a mine face including a feed operating member, a driving shaft therefor, a worm wheel and planetary driving connections between said worm wheel and driving shaft for said feed operating member, said planetary connections including a plurality of orbitally moving gears traversing their orbits at equal angular rates and having pitch line speeds bearing a predetermined ratio to each other and a plurality of mutually coaxial gears with which said orbitally moving gears cooperate, one of which is adapted to constitute a reaction member, and mechanism controlling the operation of said feeding mechanism including a plurality of jaw clutches including elements slideable longitudinally of said driving shaft, and means for rotating said cutter chain driving sprocket driving gear and said worm wheel including a driving pinion on said armature shaft, a gear meshing therewith and driven thereby, a shaft on which said last mentioned gear is fixed, a worm on

said shaft engaging said worm wheel, and a pinion on said shaft engaging said cutter chain driving sprocket driving gear.

113. In a mining mechanism, a frame carrying in rigid relation thereto a longitudinally projecting cutter bar, a motor on said frame, a cutter chain carried by said cutter bar, chain driving means operatively connected with said motor, and means for effecting movement of said frame at a cutting speed and at a higher speed including flexible feeding means, guiding means therefor, winding means rotating on a transverse axis on said frame and cooperating with said flexible feeding means, and friction controlled driving connections between the same and said motor including a transversely extending shaft operatively connected with said winding means during operation of the latter and planetary gearing coaxial therewith and comprising a plurality of sun gears and a plurality of planet gears.

114. In a mining mechanism, a frame carrying in rigid relation thereto a longitudinally projecting cutter bar, a motor on said frame, a cutter chain carried by said cutter bar, chain driving means operatively connected with said motor, and means for effecting movement of said frame at a cutting speed and at a higher speed including flexible feeding means, guiding means therefor, winding means rotating on a transverse axis on said frame and cooperating with said flexible feeding means, and friction controlled driving connections between the same and said motor including a transversely extending shaft operatively connected with said winding means during operation of the latter, planetary gearing coaxial therewith and comprising a plurality of sun gears and a plurality of planet gears, and a clutch slidably longitudinally of said shaft operative in its different positions to effect rotation of said shaft at different speeds.

115. In a mining mechanism, a frame carrying in rigid relation thereto a longitudinally projecting cutter bar, a motor on said frame, a cutter chain carried by said cutter bar, chain driving means operatively connected with said motor, and means for effecting movement of said frame at a cutting speed and at a higher speed including flexible feeding means, guiding means therefor, winding means rotating on a transverse axis on said frame and cooperating with said flexible feeding means, and friction controlled driving connections between the same and said motor including a transversely extending shaft operatively connected with said winding means during operation of the latter, planetary gearing coaxial therewith and comprising a plurality of sun gears and a plurality of planet gears, and a clutch slidably longitudinally of said shaft operative in its different positions to effect rotation

of said shaft at different speeds, said clutch operating in one position to vary the connection of parts of said planetary gearing relative to each other to effect the higher speed of drive.

116. In a mining mechanism, a frame carrying in rigid relation thereto a longitudinally projecting cutter bar, a motor on said frame, a cutter chain carried by said cutter bar, chain driving means operatively connected with said motor, and means for effecting movement of said frame at a cutting speed and at a higher speed including flexible feeding means, guiding means therefor, winding means rotating on a transverse axis on said frame and cooperating with said flexible feeding means, and friction controlled driving connections between the same and said motor including a gear coaxial with said winding means, a transversely extending shaft carrying a pinion meshing with said gear, and planetary gearing coaxial with said transversely extending shaft and including a plurality of sun gears and a plurality of planet gears.

117. In a mining mechanism, a machine frame from which a cutter bar projects in a longitudinal direction during cutting, a cutter chain, a motor carried by said frame, driving connections between said chain and motor, and means for feeding said machine during cutting including flexible means, winding means adapted to cooperate therewith rotatable on a transversely extending axis, and driving means for said winding means including a transverse shaft parallel to the axis of said winding means, driving connections between the shaft and winding means, and driving connections between the motor and shaft including planetary gearing coaxial with the latter and driven by the motor.

118. In a mining mechanism, a machine frame from which a cutter bar projects in a longitudinal direction during cutting, a cutter chain, a motor carried by said frame, driving connections between said chain and motor, and means for feeding said machine during cutting including flexible means, winding means adapted to cooperate therewith rotatable on a transversely extending axis, and driving means for said winding means including a transverse shaft parallel to the axis of said winding means, driving connections between the shaft and winding means, and driving connections between the motor and shaft including a friction brake and planetary gearing coaxial with the latter and driven by the motor and including a plurality of sun gears and a plurality of planet gears.

119. In a mining mechanism, a machine frame from which a cutter bar projects in a longitudinal direction during cutting, a cutter chain, a motor carried by said frame,

driving connections between said chain and motor, and means for feeding said machine during cutting including flexible means, winding means adapted to cooperate therewith on a transversely extending axis, and driving means for said winding means including a transverse shaft parallel to the axis of said winding means, driving connections between the shaft and winding means, and driving connections between the motor and shaft including planetary gearing coaxial with the latter and driven by the motor and including a plurality of sun gears and a plurality of planet gears and a clutch slidable longitudinally of said shaft.

120. In a mining apparatus, a machine frame provided with a cutter bar projecting longitudinally therefrom in fixed relation thereto during cutting, a motor on said frame having a longitudinally extending power shaft, a cutter chain on said bar, means for circulating the same including a gear journaled on a vertical axis at the rear of said motor, and means for feeding said frame including flexible portions, winding means, and driving means for the latter including a transversely extending shaft to the rear of said vertical axis, power transmission connections between said shaft and motor including multi-sun and planet planetary gearing coaxial with said shaft, and frictional controlling means.

121. In a mining mechanism, a frame carrying in rigid relation thereto a longitudinally projecting cutter bar, a cutter chain, a motor on said frame, driving connections between said motor and said chain, and feeding mechanism including flexible feeding means and winding means cooperating therewith including a winding member journaled on a transverse axis, a shaft parallel to said axis, driving connections between said shaft and member, and driving gearing for said shaft including orbitally moving gears fixed on a common shaft, gears concentric with said shaft and with which said first mentioned gears mesh while traversing their orbits, friction means for holding one of said last mentioned gears against rotation, an operative connection between the other of said gears and the transverse shaft, means driven by said motor for causing said first mentioned gears to travel around the first mentioned one of said second mentioned gears to cause the second mentioned of said second mentioned gears to drive said transverse shaft, and clutch mechanism movable longitudinally of said shaft.

122. In a mining mechanism, a frame carrying in rigid relation thereto a longitudinally projecting cutter bar, a cutter chain, a motor on said frame, driving connections between said motor and said chain, and feeding mechanism including flexible feeding means and winding means cooperating therewith including a winding member journaled on a transverse axis, a shaft parallel to said axis, driving connections between said shaft and member, and driving gearing for said shaft including orbitally moving gears fixed on a common shaft, gears concentric with said shaft and with which said first mentioned gears mesh while traversing their orbits, friction means for holding one of said last mentioned gears against rotation, an operative connection between the other of said concentric gears and the transverse shaft, and means driven by said motor for causing said orbitally moving first mentioned gears to travel around the first mentioned one of said second mentioned gears to cause the second mentioned of said second mentioned gears to drive said transverse shaft.

123. In a mining mechanism, a frame carrying in rigid relation thereto a longitudinally projecting cutter bar, a cutter chain, a motor on said frame, driving connections between said motor and said chain, and feeding mechanism including flexible feeding means and winding means cooperating therewith including a winding member journaled on a transverse axis, a shaft parallel to said axis, manually controllable driving connections between said shaft and member, and driving gearing for said shaft including orbitally moving gears fixed on a common shaft, gears concentric with said shaft and with which said first mentioned gears mesh while traversing their orbits, friction means for holding one of said last mentioned gears against rotation, an operative connection between the other of said gears and the transverse shaft, and means driven by said motor for causing said first mentioned gears to travel around the first mentioned one of said second mentioned gears to cause the second mentioned of said second mentioned gears to drive said transverse shaft.

124. A room and pillar mining machine including a motor having its armature shaft rotatable on an axis extending longitudinally of the machine, a bevel driving pinion upon the rear end of said shaft, a vertical shaft arranged to the rear of said armature shaft and carrying a bevel gear adjacent the upper end thereof meshing with said driving pinion, a cutter chain driving sprocket, a driving connection between said vertical shaft and said driving sprocket, and mechanism driven by said motor for feeding said machine bodily laterally along a mine face during cutting including a feed operating member rotatable upon a horizontal axis, and actuating means therefor including a worm rotatable upon a vertical axis.

125. A room and pillar mining machine including a motor having its armature shaft

- rotatable on an axis extending longitudinally of the machine, a bevel driving pinion upon the rear end of said shaft, a vertical shaft arranged to the rear of said armature shaft and carrying a bevel gear adjacent the upper end thereof meshing with said driving pinion, a cutter chain driving sprocket, a driving connection between said vertical shaft and said driving sprocket, and 5 mechanism driven by said motor for feeding said machine bodily laterally along a mine face during cutting including a feed operating member rotatable upon a transversely extending axis, and actuating means therefor 10 including a worm rotatable upon a vertical axis.
126. A room and pillar mining machine including a motor having its armature shaft rotatable on an axis extending longitudinally of the machine, a bevel driving pinion upon the rear end of said shaft, a vertical shaft arranged to the rear of said armature shaft and carrying a bevel gear adjacent the upper end thereof meshing with 15 said driving pinion, a cutter chain driving sprocket, a driving connection between said vertical shaft and said driving sprocket, and feeding mechanism for feeding said machine bodily laterally along a mine face including 20 a feed operating member rotatable upon a horizontal axis, and friction controlled actuating means therefor including a worm rotatable upon a vertical axis.
127. A room and pillar mining machine including a motor having its armature shaft rotatable on an axis extending longitudinally of the machine, a bevel driving pinion upon the rear end of said shaft, a vertical shaft arranged to the rear of said armature 25 shaft and carrying a bevel gear adjacent the upper end thereof meshing with said driving pinion, a cutter chain driving sprocket, a driving connection between said vertical shaft and said driving sprocket, and feeding mechanism for feeding said machine bodily laterally along a mine face including 30 a feed operating member rotatable upon a transversely extending axis, and friction controlled actuating means therefor including a worm rotatable upon a vertical axis.
128. A room and pillar mining machine including a motor having its armature shaft rotatable on an axis extending longitudinally of the machine, cutting mechanism including a cutter chain driving sprocket, a driving gear therefor coaxial therewith, a driving pinion meshing with said last mentioned driving gear and rotatable on a vertical axis, a shaft upon which said last mentioned pinion is mounted, driving connections for said shaft including bevel gears carried respectively thereby and by said armature shaft, and feeding mechanism for feeding said machine bodily laterally along 35 a mine face including a feed operating member, and operating means therefor driven by said motor including a shaft extending transversely of said machine and in a vertical plane including a line parallel 40 to a line parallel to the axis of rotation of the cutter chain sprocket, and driving means for said last mentioned shaft including worm driving gear and clutch mechanism including a clutch element reciprocable 45 longitudinally of said transversely extending shaft.
129. A room and pillar mining machine including a motor having its armature shaft rotating on an axis extending longitudinally of the machine, a cutting mechanism including a cutter chain driving sprocket, a driving gear therefor coaxial therewith, and mechanism driven by said motor for feeding said machine bodily laterally along 50 a mine face including a feed operating member and driving mechanism therefor including a worm rotating upon a vertical axis and in a direction opposite to the direction of rotation of said driving gear said 55 vertical axis extended passing within the periphery of said driving gear.
130. A room and pillar mining machine including a motor having its armature shaft rotating on an axis extending longitudinally of the machine, a cutting mechanism including a cutter chain driving sprocket, a driving gear therefor coaxial therewith, and mechanism driven by said motor for feeding said machine bodily laterally along 60 a mine face including a feed operating member rotatable upon a transverse axis and driving mechanism therefor including a worm rotating upon a vertical axis and in a direction opposite to the direction of rotation of said driving gear.
131. In a mining mechanism, a frame carrying in rigid relation thereto a longitudinally projecting cutter bar, a cutter chain, a motor on said frame, driving connections between said motor and said chain, and feeding mechanism including a flexible member and winding means cooperating therewith including a winding member 65 journaled on the frame, and driving gear 70 ing for said winding member including orbitally moving gears fixed on a common shaft, a plurality of coaxially arranged gears with which said first mentioned gears mesh while traversing their orbits, friction means for holding one of said concentric gears against rotation, an operative connection between the other of said concentric gears and the winding member, and means 75 driven by said motor for causing said orbitally moving gears to travel around the first mentioned one of said second mentioned gears to cause the second mentioned one of said second mentioned gears to drive 80 said winding member.

132. In a mining mechanism, a frame carrying in rigid relation thereto a longitudinally projecting cutter bar, a cutter chain, a motor on said frame, driving connections between said motor and said chain, and feeding mechanism including a flexible member and winding means cooperating therewith including a winding member journaled on the frame, and driving gear 5 for said winding member including coaxial orbitally moving gears fixed on a common shaft, a plurality of coaxially arranged gears with which said first mentioned gears mesh while traversing their orbits, friction 10 means for holding one of said concentric gears against rotation, an operative connection between the other of said concentric gears and the winding member, means driven by said motor for causing said orbitally moving gears to travel around the first mentioned one of said second mentioned gears to cause the second mentioned one of said second mentioned gears to drive said winding member, and means operative when 15 said friction means is inoperative to cause said gearing to effect a faster rotation of said winding member.

133. A room and pillar mining machine including a motor having an armature shaft 20 rotatable on an axis extending longitudinally of the machine, a cutter chain driving sprocket, driving means therefor actuated by said motor and including an element rotating on a vertical axis, said element on 25 rotation carrying therewith a worm, and means for feeding said member by power from said motor including a flexible feeding member, a cooperating feed operating member rotatable on a transverse axis, two 30 coaxial gears of different size, one of said coaxial gears being connected to said feeding device, planet gears meshing respectively with said two coaxial gears and rotating together; a connection from said driving motor 35 through said worm for driving said planet gears around the axis of said coaxial gears; and a releasable brake acting on the other coaxial gear.

134. A room and pillar mining machine 40 including a motor having an armature shaft rotatable on an axis extending longitudinally of the machine, a cutter chain driving sprocket, driving means therefor actuated by said motor and including an element rotating on a vertical axis, said element on 45 rotation carrying therewith a worm, and means for feeding said machine by power from said motor including a flexible feeding member, a cooperating feed operating member 50 rotatable on a transverse axis, an element driven by said driving motor through said worm, two members between which said element is interposed and produces a reaction, one of said members being connected to said

feeding device, and a releasable brake acting on the other of said members.

135. A room and pillar mining machine including a motor having an armature shaft rotatable on an axis extending longitudinally of the machine, a driving pinion thereon, a gear driven thereby, a shaft supporting and driven by said gear, a worm fixed on said shaft adjacent said gear, a driving pinion on said shaft at the opposite side of said worm from said gear, cutting mechanism including a cutter bar extending during cutting longitudinally of said frame and carrying a circulating cutter chain, a cutter chain driving sprocket and operative 50 connections between said sprocket and said second mentioned driving pinion, and mechanism for feeding said machine laterally during cutting including a flexible feeding member, a feed operating member and driving mechanism therefor driven by said worm and including a gearing through which said feed operating member is driven, said gearing including an element driven by said motor and two members between 55 which said element is interposed and produces a reaction, one of said members being connected to said feeding device, a stationary part, and a releasable friction mechanism acting to connect parts of said gearing through said second member to the stationary part.

136. A room and pillar mining machine including a motor having an armature shaft rotatable on an axis extending longitudinally of the machine, a driving pinion thereon, a gear driven thereby, a shaft supporting and driven by said gear, a worm fixed on said shaft adjacent said gear, a driving pinion fixed on said shaft at the opposite side of said worm from said gear, cutting mechanism including a cutter bar extending during cutting longitudinally of said frame and carrying a circulating cutter chain, a cutter chain driving sprocket and operative 100 connections between said sprocket and said second mentioned driving pinion, and mechanism for feeding said machine laterally during cutting including a flexible feeding member, a feed operating member and driving mechanism therefor driven by said worm and including two coaxial gears of 105 different size, one of said coaxial gears being connected to said feeding device, planet gears meshing respectively with said two coaxial gears and rotating together, a connection from said driving motor for driving said planet gears around the axis of said coaxial gears, and a releasable brake acting 110 on the other coaxial gear.

137. A room and pillar mining machine 115 including a motor having its armature shaft rotatable on an axis extending longitudinally of the machine, cutting mechanism including

- a cutter chain driving sprocket, a driving gear therefor coaxial therewith, feeding mechanism for summing said cutting mechanism into a face and for feeding said machine bodily laterally along the mine face including a feed operating member, a worm wheel and planetary driving connections between said worm wheel and said feed operating member, and means for rotating said cutter chain driving sprocket driving gear and said worm wheel by power from said motor including a driving pinion on said armature shaft, a gear meshing therewith and driven thereby, a shaft on which said last mentioned gear is fixed, a worm on said shaft engaging said worm wheel, and a pinion on said shaft engaging said cutter chain driving sprocket driving gear, said worm being between said gear and pinion on said shaft.
138. A room and pillar mining machine including a motor having its armature shaft rotatable on an axis extending longitudinally of the machine, a bevel driving pinion upon the rear end of said shaft, a bevel gear rotating upon a vertical axis to the rear of said armature shaft and disposed above and meshing with said driving pinion, a cutter chain driving sprocket, a driving connection between said bevel gear and said driving sprocket, feeding mechanism for feeding said machine bodily laterally along the mine face including a feed operating member rotatable upon a transversely extending axis and friction controlled actuating mechanism therefor including as a driving member a worm rotatable upon a vertical axis, and means including a flexible member, a rotatable member cooperating therewith, and a friction device for varying the resistance to rotation thereof in a paying out direction for controlling the angular position of said machine during cutting.
139. A room and pillar mining machine including a motor having its armature shaft rotatable on an axis extending longitudinally of the machine, a bevel driving pinion upon the rear end of said shaft, a bevel gear rotating upon a vertical axis to the rear of said armature shaft and disposed above and
- meshing with said driving pinion, a cutter chain driving sprocket, a driving connection between said bevel gear and said driving sprocket, mechanism for feeding said machine bodily laterally along the mine face including a feed operating member rotatable upon a transversely extending axis, a worm coaxial with and rotated by said bevel gear, a transverse shaft carrying a worm wheel driven by said worm and friction controlled driving connections between said shaft and said feed operating member including a second shaft parallel to said transverse shaft and a friction clutch controlling the driving of said second shaft by said first mentioned shaft, and means including a flexible member, a rotatable member cooperating therewith and a friction device for varying the resistance to rotation thereof in a paying out direction for controlling the angular position of said machine during cutting.
- In witness whereof, I have hereunto set my hand at Terre Haute, Indiana, this 4th day of June, A. D. one thousand nine hundred and fifteen.

FRANK CARTLIDGE.

DISCLAIMER

1,536,422.—*Frank Cartlidge*, Terre Haute, Ind. MINING MACHINE. Patent dated May 5, 1925. Disclaimer filed June 18, 1940, by the assignee, *Sullivan Machinery Company*.

Hereby enters this disclaimer to claims 102, 105, 108, 109, 110, 111, 112, 113, 114, 115, 116, 117, 118, 119, 120, 121, 122, 123, 131, and 132. And further disclaims the combinations defined in claims 84, 85, 86, 89, and 90, except wherein the transverse members thereof are laterally displaced with respect to each other.

[*Official Gazette July 9, 1940.*]
